LAURENCE A. HAWKINS AND ELMER F. BLISS, OF SCHENECTADY, NEW YORK, ASSIGNEES, BY MESNE ASSIGNMENTS, TO THE UNION SWITCH AND SIGNAL COMPANY, A CORPORATION OF PENNSYLVANIA.

NORMAL-DANGER-SIGNAL SYSTEM.

1,086,706.

Specification of Letters Patent. Patented Feb. 10, 1914.

Application filed April 4, 1910. Serial No. 553,250.

To all whom it may concern:

Be it known that we, LAURENCE A. HAWKINS and ELMER F. BLISS, citizens of the United States, residing at Schenectady, 5 county of Schenectady, State of New York, have invented certain new and useful Improvements in Normal-Danger-Signal Systems, of which the following is a specification.

10 Our invention relates to block signal systems in which the signals stand normally at danger and in which the signals are adapted to indicate danger, caution and clear, either by means of a three-position arm or by the equivalent arrangement of two two-position arms.

15 The object of our invention is to provide a simple circuit arrangement, for properly controlling the signals, involving a small 20 number of line wires.

In a normal danger system of the type to which our invention relates, it is essential that when a train is in one block and two blocks ahead are clear, that the signal immediately in advance of the train should have been moved to the clear position, and the next signal in advance to the caution position. The train must thus control two signals in advance of it, and the signal two blocks ahead must control the clear position of the signal immediately in advance of the train. We accomplish this result by means 30 of two line wires extending through each block in addition to the common wire. One 35 of these wires is the clearing wire which, when the train enters a block, clears or holds clear the signal next in advance, and the other is the control wire through which the clear position of a signal is controlled from 40 the signal next in advance.

Our invention consists in arranging connections controlled by the track relay of a block for varying the resistance of the control circuit for that block and providing 45 means responsive to the variation resistance in that circuit for closing the clearing circuit of the block next in advance.

Our invention will best be understood by reference to the accompanying drawing 50 which shows diagrammatically a normal danger signal system arranged in accordance with our invention.

In the drawing, A, A¹, A² and A³ represent the rails of four successive blocks.

B, B¹ and B² represent track batteries. 55

C—C³ represent track relays for the blocks which form with the rails and batteries closed track circuits.

D—D³ are the signals, which normally stand at danger and which are adapted to indicate danger, caution and clear.

E—E³ represent relays controlled by the track relays and controlling the caution indications of the signals.

F—F³ represent relays each controlled by 65 the signal in advance and controlling the clear position of the signal at which it is placed.

G—G³ represent relays, the purpose of which will be explained. 70

H—H³ represent resistances.

I—I³ represent batteries for supplying current to the operating mechanisms of the signals.

J—J³ represent contacts which are shown 75 in the conventional manner as operated by the signal mechanisms.

K represents the common wire.

L—L³ represent the clearing wires and M—M³ represent what we have termed 80 "control wires."

The operation of the system is as follows:—With a train occupying block A, as is indicated in the drawing, the track relay C is deenergized. The relay E has its circuit 85 open at the upper contact of track relay C so that current is cut off from signal D. Relays E¹ and F¹ at signal D¹ are both energized so that this signal is in clear position. The circuit of relay E¹ may be traced from 90 the upper terminal of battery I¹ through relay E¹, upper contact of track relay C¹, clearing wire L, middle finger and back contact of track relay C and through common wire K back to the battery. The circuit of 95 relay F¹ may be traced from the upper terminal of battery I² through resistance H², relay G², contact J², control wire M¹, lower finger and front contact of track relay C¹, relay F¹ to common wire K and back to battery. The circuit which has just been traced includes contact J². This contact is closed because signal D² is in caution position, relay E² being energized. The circuit of relay E² may be traced from the upper 105 terminal of battery I² through relay E², upper contact of relay C², clearing wire L¹, middle finger and front contact of relay C¹.

contact of relay G^1 , wire L , middle finger and back contact of relay C to common wire K and back to battery. This circuit which has just been traced includes the contacts of relay G^1 . This relay is energized through the following circuit:—from upper terminal of battery I^1 , through resistance H^1 , relay G^1 , contact J^1 , control wire M , lower finger and back contact of relay C to common wire K and back to battery.

It will be noted that the circuit which was traced for relay F^1 passes through the winding of relay G^2 . This latter relay, however, is not energized since it is a relay of low resistance compared to relay F^1 . For instance, the relative resistances of these two relays may be 16 and 1000 ohms respectively, as is indicated on the drawing, so that when the circuit is closed through the two relays in series, enough current flows to energize relay F^1 but not sufficient to energize relay G^2 . Now, when the train advances from block A into block A^1 the following changes take place: Relay C^1 is deenergized and opens the circuit of relay E^1 which cuts off the battery from signal D^1 and puts that signal at stop. Lower finger of relay C^1 in passing from its front to its back contact cuts relay F^1 out of circuit and connects line wire M^1 directly to common. This lowers the resistance of the circuit containing relay G^2 and enough current now flows to energize this relay and causes it to close its contacts. This closing of its contacts connects clearing wire L^2 through the middle finger and front contact of relay C^2 and contact of relay G^2 to clearing wire L^1 which is connected through the middle finger and back contact of relay C^1 to common. This energizes relay E^2 so that signal D^3 is moved to caution. Contact J^3 is thereby closed connecting battery I^3 through control wire M^2 to relay F^2 causing signal D^2 to move to clear position.

It will be noted from the above that the control wire M^1 performs two functions—first, when the train is in block A to connect relay F^1 to contact J^2 , controlled by signal D^2 and thereby place signal D^1 under control of signal D^2 . Second, when the train enters block A^1 , at which time signal D^1 goes to stop position and relay F^1 is no longer needed, this control wire M^1 serves to energize relay G^2 , which, when energized, closes the clearing circuit L^2 for the signal D^3 .

Resistances $H—H^3$ are placed in series with the relays $G—G^3$ to limit the current drawn from the battery to the proper amount when the high resistance relays $F—F^3$ are cut out of circuit. With the relative resistances indicated for relays G and F , resistance H may be 100 or 150 ohms. Of course these values of resistances are merely illustrative and may be varied as desired.

Instead of cutting relays F , F^1 , etc., out of circuit by open-circuiting them, they may,

obviously, instead, be cut out of circuit by short circuiting. This arrangement is shown for relay F^3 which is simply short circuited by the lower finger and back contact of relay C^3 when that relay is deenergized.

We do not desire to limit ourselves to the particular connections and arrangements of parts shown and described but aim, in the appended claims, to cover all modifications which are within the scope of our invention.

What we claim as new and desire to secure by Letters Patent of the United States, is,—

1. In a normal danger signaling system, a plurality of closed track circuits including track relays, signals for the blocks adapted to indicate danger, caution and clear, two line circuits extending through each block, means included in one of said line circuits for controlling the caution indication of the signal for the block in advance and means connected with the second line circuit for controlling the clear indication of the block in accordance with said caution indication of said signal in advance, connections controlled by the track relay of each block for varying the resistance of said second line circuit, and means responsive to said varying of resistance for sending current through the line circuit of the block in advance which includes the means for controlling the caution indication of the signal in advance of said block in advance.

2. In a railway signaling system, a plurality of blocks, sources of current and track relays connected with the blocks, signals for the blocks adapted to indicate clear, caution and danger, a circuit for each signal including means for the control of the caution indication of the signal which circuit is controlled by the track relay of the preceding block, an auxiliary relay for each block and a circuit therefor, means for the control of the clear indication of each signal, contacts and connections controlled by each track relay for including said means in and excluding it from the circuit of the auxiliary relay for the next succeeding block the auxiliary relay being responsive to the variation in the resistance of the circuit caused by such inclusion and exclusion, and connections controlled by each auxiliary relay when closed for closing the circuit of the means for controlling the caution indication of the next succeeding signal.

3. In a railway signaling system, a plurality of blocks, sources of current and track relays connected with the track rails of the blocks, signals for the blocks adapted to indicate clear, caution and danger; a caution indication relay and a clear indication relay for each signal, a circuit for each caution relay controlled by the track relay of the preceding block, an auxiliary relay for each block and a circuit therefor, contacts and connections controlled by each track relay

- for including the clear indication relay of the corresponding block in and excluding it from the circuit of the auxiliary relay for the next succeeding block, the last mentioned circuit being proportioned so that the auxiliary relay is open or closed according to whether or not the clear indication relay is included in the circuit, and a contact and connections controlled by each auxiliary relay for closing the circuit of the caution relay for the next succeeding block when the auxiliary relay is closed.
4. In a railway signaling system, a plurality of blocks, sources of current and track relays connected with the track rails of the blocks, signals for the blocks adapted to indicate clear, caution and danger; a caution indication relay and a clear indication relay for each signal, a circuit for each caution relay controlled by the track relays for the corresponding block and for the next preceding block; an auxiliary relay for each signal and a circuit therefor including a contact controlled by the corresponding signal, contacts controlled by each track relay for including the clear indication relay for the corresponding block in and excluding it from the circuit of the next succeeding auxiliary relay, the last-mentioned circuit being so proportioned that when closed the auxiliary relay is open or closed according to whether or not the clear indication relay is included in the circuit, and that the clear indication relay is closed when included in the circuit, and a contact and connections controlled by each auxiliary relay for connecting the caution indication relay for the next succeeding signal with the circuit of the caution indication relay for the corresponding signal.

In witness whereof, we have hereunto set our hands this first day of April, 1910.
